CARTON

George V. Skowronski, Neenah, Wis., assignor to American Can Company, New York, N.Y., a corporation of New Jersey

Filed Feb. 16, 1961, Ser. No. 89,762
7 Claims. (Cl. 229—51)

This invention relates to a tamperproof, reclosable carton which may be made from a single blank. More 10 specifically, the invention relates to a carton for packaging ice cream and other articles, having a reclosable cover or lid.

Ice cream is customarily packaged in either cartons employing conventional end locking means or cylindrical containers. Both of the aforementioned packaging means have serious drawbacks. The use of locking means involves greater detail in die cutting for the blank than does a carton that is sealed by adhesive. If the locking means is improperly cut or distorted, the carton 15 may open prior to use by the user. Cylindrical containers cost more to produce than do rectangular cartons. Further use of a cylindrical container is uneconomical in regard to storage space both for the seller of the packaged ice cream and the consumer. Also, the cylindrical package does not readily lend itself to equal division of the contents by slicing as does a rectangular package.

A typical locked end carton is shown in FIGURE 4 of U.S. Patent No. 2,760,713, wherein the length along the longitudinal edge of the carton is substantially greater than the height. When the contents are removed from the end of such carton the hand must penetrate further into the carton than when removing the contents through the top so that the chance of getting ice cream on the hand is greatly increased.

If end locks are employed, the user is likely to overlook any top opening means which may be present, and thus only opens the locked end panels to gain access to the contents. The use of sealed end panels in place of the locking panels shown in the aforementioned patent discourages the end opening of the carton, and conversely encourages removal of the contents through the larger top opening, which is in fact more convenient. Further, the sealed end carton gives a stronger construction than does the locked end carton. The use of the strongest construction possible for a given weight board is especially important in the packaging of ice cream which presents a unique problem. When loaded, the ice cream is in a plastic semifluid state. As the ice cream is frozen after loading, it expands exerting pressure on the carton making a strong carton construction very advantageous.

From the standpoint of storage space, utility and convenience the ideal packaging means is a parallelepiped, sealed end, top opening carton which has an adhesively secured opening means. Such a carton is tamperproof since the tearing of either the sealed ends or the opening feature is readily ascertainable. Generally, previous top opening cartons have not been satisfactory from several standpoints. Some of the cartons are constructed for top filling and hence cannot be employed with existing end loading machinery. When constructed for top filling, difficulty has been encountered in making the cartons substantially tamperproof. When the type of carton shown in the aforementioned patent is opened from the top, there is a tendency for the top panel to tear along the score lines defining the lateral edges thereof. This is due to two factors. One, there is a bond formed between the ice cream and the inside surface of the top panel. Secondly, the flaps which are hingedly attached to the lateral edges of the top panel are frictionally en-

2

gaged by the locked end panels. Due to the factors noted above, the tear resistance of the top panel is overcome and ripping occurs at the intersection of the lateral score lines with the front longitudinal edge of the top panel.

The flaps hingedly attached to the lateral edges of the top panel of the carton of the aforementioned patent complicate reclosure once the carton has been opened. When the top panel is swung back about the score line defining the rear longitudinal edge of the top panel, the flaps attached to the lateral edges of the top panel disengage from their frictional contact with the locked end panels and swing outwardly. In order to engage the flaps upon reclosure, it is necessary to insert the flaps in their original position inside of and adjacent to said locked end panels which is both time consuming and inconvenient.

A primary object of the present invention is to provide a tamperproof top opening carton which opens readily without any tearing or peeling of the carton panels.

Another object of the present invention is to provide a top opening carton with a tear strip opening means and which can be readily reclosed without the tucking in of locks or flaps.

Yet another object of the present invention is to provide a carton which by its construction directs the user to employ the top opening means and not to open the end panels.

Still another object of the present invention is to provide a top opening carton with a hinged cover portion which telescopes over the receptacle portion so that none of the flaps or panels protrude from the reclosed carton.

Another object of the present invention is to provide an end loading carton that is adaptable to existing filling machinery.

Further details, advantages and objects of the invention will be apparent from the following specification and appended drawings wherein:

FIGURE 1 folded upon itself and having certain cut and scored to form a carton having a reclosable lid,

FIGURE 2 is a plan view of the blank shown in FIGURE 1 folded upon itself and having a certain superposed portions adhered together as a step in making a carton from the blank,

FIGURE 3 is a fragmental perspective of the folded blank shown in FIGURE 2 partially set up,

FIGURE 4 is a fragmental perspective of the same partially set-up blank at a further stage in being set up,

FIGURE 5 is a fragmental perspective of the same partially set-up blank at still a further stage,

FIGURE 6 is a fragmental perspective of the completed carton showing the cover in closed and sealed condition,

FIGURE 7 is a fragmental perspective of the completed carton showing the tear strip partially removed, and

FIGURE 8 is a perspective view showing the carton opened and the cover folded back.

Referring to FIGURE 1, the carton is made of a single foldable blank "A" of flexible material such as paper-board. The blank is divided by score lines 10-18 and cut lines 32 and 33 into hingedly connected panels and flaps including opening panel 40, top panel 41, back panel 42, bottom panel 43, front panel 44, opening flaps 45, top flaps 46, end flaps 47, bottom flaps 48 and end flaps 49.

A tear strip comprising 45b and 40b is defined by perforated score lines 19 and 20 in opening flaps 45 and opening panel 40. Top flaps 46 are divided into portions 46a, 46b and 46c by perforated score lines 21, 22 and 23 and by holes 30. End flaps 47 are notched arcuately at 31 as shown. The function of the perforated score lines, holes and notches will be more fully described hereinafter.

The blank A is formed into a glued carton shell by folding front panel 44 about score line 13 to lie directly superposed on bottom panel 43, applying adhesive on the exposed surface 40c and then folding panels 40 and 41 about score line 11 so that the adhesive bearing surface overlies and becomes adhered to the exposed surface of panel 44 adjacent score line 13. In such condition, as shown in FIGURE 2, the shell may be shipped economically to the product packager for set-up, filling and sealing.

FIGURE 3 depicts an initial stage in which the carton is squared and ready for filling. Usually one end is closed and sealed, the carton filled and then the other end closed and sealed. Since both closing and sealing steps are the same, reference is had to closing just one end of the carton. When the shell is squared panels 41, 42, 43 and 44 are positioned consecutively at right angles to each other. Opening panel 40 bears the same relation to panels 41, 42 and 43 as does panel 44 on which it is directly super-imposed.

In closing the carton, bottom flap 48 is folded inwardly about score line 17 to a position perpendicular to bottom panel 43 as shown in FIGURE 4. Then end flap 49 is folded inwardly about score line 18 to overlie bottom flap 48. The inner surface of opening flap 45 between score line 20 and the bottom edge is coated with adhesive and the flap folded inwardly about score line 14 to overlie and become adhered to end flap 49. Adhesive is applied to the inner surfaces of end flaps 47 adjacent the outer edges. End flap 47 is then folded inwardly about score line 16 and adhered to end flap 49 to give the configuration shown in FIGURE 5. To complete the closing, adhesive is applied to the inner surface of top flap 46 on that portion of 46a which will abut 45a when the carton is closed, and on portion 46c, following which flap 46 is infolded on score line 15 and adhered to the subposed flaps. Since top flap 46 completes and adheres the end closure, the step of adhering portion 45c of opening flap 45 to end flap 49 may be omitted. The closed carton as it appears to the consumer, prior to opening, is shown in FIGURE 6.

Referring to FIGURE 7, in opening the carton the tear strip is grasped at the end portion 45b which is visible through hole 30 in top flap 46 and pulled outward and toward front panel 44. This causes a tearing action along the several perforated score lines. Portion 46b tears along perforation lines 22 and 23, dropping out when the edge of flap 46 adjacent the front panel 44 is reached. Underlying portion 45b tears along perforation lines 19 and 20, throughout the length of opening panel 40 and into the opposite opening flap 45 until the hole on the opposite end is reached, at which time the tear strip drops free. In order to reach the contents in the carton, it is merely necessary to pull upwardly on the free edge of portion 40a which causes a separation of portion 46a and 46c of top flaps 46, along perforated score line 21.

When the carton is completely opened as shown in FIGURE 8 opening panel 40, opening flaps 45 and top flaps 46 have each been separated into cover and receptacle portions. The cover portion which includes top panel 41, panel portion 40a and flap portions, 45a and 46a is hingedly connected along score 11 to the receptacle portion. Receptacle panel portion 40c, panels 42, 43 and 44, flap portion 45c and end flap 49 comprise the receptacle portion of the carton. Since the cover walls are connected at the front corners of the carton, there are no loose flaps projecting from the lateral edges of the top panel when the carton is open. In reclosing the carton, the cover portion is merely lowered so that the appearance of the carton is essentially the same as when the tear strip was removed. The necessity of reinserting the top flaps is obviated because the cover walls are connected and close over the outer surface of the corresponding receptacle walls.

The present invention provides a carton construction using an integral blank. The carton can be readily set up, filled with the commodity to be packaged, and sealed by automatic machinery. The carton is tamperproof because it can not be opened without revealing tearing along the perforated score lines. There are no loose flaps to either cause inconvenience to the user or else to distract from the appearance of the carton. The carton can be opened and closed numerous times without losing its rigid construction.

It is to be understood that the description of the carton construction given herein is merely illustrative of the essential features of the invention, and is not limited to the specific dimensions or contours which may be greatly varied or modified and which variations are intended to be included within the scope of the appended claims.

I claim:

1. A tamperproof, reclosable carton, formed of a single blank, suitably cut and scored to provide a carton having hingedly connected end flaps, and front, back and bottom panels; a top panel hingedly connected to the upper edge of said back panel; an opening panel hingedly connected along the front edge of said top panel and having opening flaps hingedly attached to the end edges thereof, said opening panel and opening flaps overlying and adhered adjacent to their lower edges to said front panel and end flaps respectively; top flaps hingedly connected to the end edges of said top panel overlying and adhered to said opening flaps in the area adjacent their upper edges; and a continuous tear strip defined by a pair of spaced lines of weakness extending from a free edge of one of said opening flaps throughout the entire length of said opening panel to a free edge of the other opening flap.
2. A tamperproof reclosable carton formed of a single blank suitably cut and scored to provide a carton having hingedly connected end flaps and front, back and bottom panels; bottom flaps coextensive in area with the ends of said carton hingedly connected to the end edges of the bottom panel and underlying said end flaps; a top panel hingedly connected to the upper edge of said back panel; an opening panel coextensive in area with said front panel hingedly connected along the front edge of said top panel and having opening flaps hingedly attached to the end edges thereof, said opening panel and opening flaps overlying and adhered adjacent to the lower edge to said front panel and end flaps respectively; top flaps hingedly connected to the end edges of said top panel overlying and adhered to said opening flaps in the area adjacent to their upper edges; and a continuous tear strip defined by a pair of spaced lines of weakness extending from a free edge of one of said opening flaps throughout the entire length of said opening panel and to a free edge of the other opening flap.
3. A tamperproof, reclosable carton formed of a single blank suitably cut and scored to provide a carton having hingedly connected front, back and bottom panels; bottom flaps coextensive in area with the ends of said carton hingedly connected to the end edges of the bottom panel; end flaps overlying said bottom flaps hingedly connected to the end edges of said front and back panels; a top panel hingedly connected to the upper edge of said back panel; an opening panel coextensive in area with said front panel hingedly connected along the front edge of said top panel and having opening flaps attached to the end edges thereof, said opening panel and opening flaps overlying and adhered adjacent to their lower edges to said front panel and end flaps respectively; top flaps hingedly connected to the end edges of said top panel overlying and adhered to said opening flaps in the area adjacent to their upper edges; and a continuous tear strip defined by a pair of spaced lines of weakness extending from a free edge of one of said opening flaps throughout the entire length of said opening panel to a free edge of the other opening flap.

4. The carton of claim 1 wherein said top flaps, coextensive in area with said end flaps, have their central portions removed to expose the ends of said tear strip, and have cut score lines substantially coincident with the cut score lines defining said tear strip so that removal of the tear strip removes a portion from each of the top flaps.

5. A tamperproof reclosable carton formed of a single blank suitably cut and scored to provide a carton having hingedly connected front, back and bottom panels and end flaps; a top panel hingedly connected to the upper edge of said back panel; an opening panel coextensive in area with said front panel hingedly connected along the front edge of said top panel and having opening flaps hingedly attached to the end edges thereof, said opening panel and opening flaps overlying and adhered adjacent to their lower edge to said front panels and end flaps, respectively; top flaps coextensive in area with said end flaps hingedly connected to the lateral edges of said top panel and having therein a hole formed by removing a central portion therefrom, a pair of horizontal, parallel spaced cut score lines in each top flap extending from said hole to the front edge of said flap, and a cut score line extending from said hole upwardly to the back edge of said flap; said top flaps overlying and adhered to said said opening flaps in the area adjacent to their upper edges; a continuous tear strip defined by a pair of parallel, straight, spaced cut score lines extending from a free edge of one of said opening flaps located beneath the hole in said top flap underneath and between said cut score lines in said opening flap through the entire length of said opening panel underneath and between the parallel cut score lines in the other top flap to a free edge of the other opening flap beneath the hole in the said other top flap so that when the tear strip is removed the carton is divided into a cover portion and a receptacle portion.

6. A tamperproof, reclosable carton formed of a single blank, said blank being suitably cut and scored to provide consecutive front, bottom, back, top and opening panels hingedly connected together; opening flaps hingedly connected to the end edges of the opening panel; end flaps connected to the end edges of at least one of said front, bottom and rear panels; said blank being folded to provide a carton having said opening panel and opening flaps superposed over said front panel and end flaps

5

respectively, at least one of said opening panels and opening flaps adjacent an edge remote from the top panel being adhered to a respective subposed front panel and end flap; top flaps hingedly connected to the end edges of the top panel and folded into face-to-face position with the adjacent opening flaps, said top and opening flaps being adhered together; and a pair of spaced lines of weakness extending between the plane of the top panel and the area of adhesion of the opening panels and opening flaps to the front panel and end flaps, said lines of weakness at each end terminating at a free end of said opening panel and opening flaps, said lines of weakness defining a tear strip positioned between the plane of the top panel and the area of adhesion of one of said opening panel and opening flaps to a subposed front panel and end flap.

7. A carton formed of an integral blank cut and scored to provide a bottom, a rear wall, an inner front wall member, and inner end wall members, complementary rear and front outer end wall members on the end edges of said rear wall and said inner front wall member disposed in overlapping relation to said inner end wall members, said rear wall, inner front wall member and inner end wall members being of uniform height, a cover hingedly connected to the upper edge of said rear wall and provided with end flaps, an outer front wall member on the swinging edge of said cover provided with end flaps disposed in overlapping relation to said outer end wall members, said cover end flaps being disposed in overlapping relation to and secured to upper portions of said end flaps on said outer front wall member, said outer front wall member and its said end flaps having vertically spaced fracturing scores extending throughout the length thereof, said outer front wall member being secured to said inner front wall member and its end flaps being secured to outer end wall members below the lower of said fracturing scores.
